SANDER

John Howard King, Mansfield, Ohio

Application September 20, 1938, Serial No. 231,351

3 Claims. (Cl. 51—102)

My invention relates to the surfacing of wood material and the like and includes among its objects and advantages the provision of an improved abrading machine.

An object of my invention is to provide an abrading machine commonly designated a sander wherein novel means is incorporated to facilitate the execution of precision work.

Another object is to provide an abrading machine embodying a work table and a rotary abrading drum mounted thereabove in which novel pressure rolls are associated with the abrading drum in such manner as to effectively straighten the work as it passes across the face of the drum to the end that the work may be abraded to uniform thickness.

A further object is to provide an abrading machine including a work table and a sanding drum adjustably related thereto in which novel pressure rolls are operatively associated with the drum for adjustment therewith and in which novel means are incorporated for simultaneously adjusting the drum and the pressure rolls.

In the accompanying drawings:

Figure 1 is a top plan view of a machine embodying my invention with a part removed;

Figure 2 is a side elevational view;

Figure 3 is a sectional view along the line 3—3 of Figure 1;

Figure 4 is a sectional view along the line 4—4 of Figure 1;

Figure 5 is a sectional view along the line 5—5 of Figure 2;

Figure 6 is a sectional view along the line 6—6 of Figure 4; and

Figure 7 is a sectional view along the line 7—7 of Figure 5.

In the embodiment selected to illustrate my invention, I make use of a work support or table 10 which functions as a base for the machine. On the upper face of the table 10 I mount upright walls 12 each of which comprises sections 14 and 16. A drum 18 is positioned above the work table 10 and is connected with a shaft 20 having its ends journaled in blocks 22 slidably related to the walls 12. Drum 18 includes the usual V-shaped trough 24 within which the ends 26 of the sand paper or other abrading sheet 28 are positioned and made secure by the key strip 30 and bolts 32. Such fastenings are well-known in the art and need not be described in further detail.

Figures 4 and 6 illustrate the manner in which the blocks 22 are slidably related to their respective walls 12. According to Figure 6, the sections

14 and 16 of the wall 12 are spaced and their vertical edges are grooved at 34 for slidably receiving the vertical edges of the block 22. To each block 22 I fixedly connect a screw 36 by a key 38, and the screws 36 extend loosely through openings 40 in a plate 42 which interconnects the side walls 12. Each screw 36 has threaded relation with a sprocket 44 which lies adjacent the upper face of the plate 42 and is connected with a sprocket chain 46.

Adjacent the upper faces of the sprockets 44 I position compression springs 48 which are held under tension by brackets 50 connected to the plate 42 by bolts 52 which may extend through the plate 42 and have threaded relation with the side walls 12 for connecting these parts into a unitary structure. Upon the plate 42 and substantially intermediate the sprockets 44 I mount a sprocket 54 which has connection with the chain 46 for actuation purposes. A handle 56 is fixedly connected with the sprocket 54 to facilitate turning thereof. Sprocket 54 is rotatably mounted on a shaft 58 having a shank 60 extending through a slot 62 in the plate 42. A nut 64 is threaded on to the shank 60 for drawing the shoulder 66 of the shaft 58 against the plate 42 for securing purposes. The shaft 58 may be provided with a flange 68 to restrain the sprocket from relative movement longitudinally of the shaft.

Rotation of the sprocket 54 imparts motion to the chain 46 which in turn rotates the sprockets 44. Screws 36 are keyed to the blocks 22, but the sprockets 44 have threaded connection with the screws so that rotation of the sprocket raises or lowers the screws depending upon the direction of rotation of the sprocket 54. Since the drum 18 is carried by the blocks 22, adjustment of the screws 36 will impart corresponding adjustment to the drum 18 for accurately locating the same with respect to the work table 10. The screws 36 are turned simultaneously and are of the same pitch so that the drum 18 will always take a position in parallel relation with the work table. In Figures 1, 3 and 4 I illustrate pressure rolls 70 associated with the drum 18 in such manner as to press the work 72 against the work table 10. To each of the blocks 22 I pivotally connect a pair of bell cranks 74, as at 76. According to Figure 4, the bell cranks 74 have their reaches 78 extending in opposite directions and having supporting connection with shafts 80 which support the pressure rolls 70. The spring 82 of Figure 4 interconnects the bell cranks 74 in such manner as to urge the pressure rolls 70.

downwardly against the work 72. In the same view, I illustrate a stop pin 84 anchored to the block 22 for limiting the downward movement of the pressure rolls 70. The bell cranks are recessed to provide shoulders 86 which, in the absence of the work 72, abut the stop pin 84 for limiting downward movement of the pressure rolls.

10 Springs 82 will yield when the work 72 is pushed underneath the pressure rolls. The tension of the springs 82 is such as to effectively bend thin work flat against the work table 10 so that the finished work will be of uniform thickness. Drum 18 is easily and quickly adjusted to accommodate 15 work of variable thickness through the medium of the sprocket 54. Such adjustment of the drum 18 simultaneously raises or lowers the bell cranks 14 which in turn causes the pressure rolls 70 to be adjusted with the drum 18. Stops 84 are so 20 related to the shoulders 86 as to permit the pressure rolls to take normal positions beneath the drum 18 so as to have pressure relation with the work. Figure 6 illustrates the sections 14 and 16 as being recessed at 88 for housing the bell cranks 25 74. In thus housing the bell cranks, the pressure rolls 70 may embody lengths greater than the width of the work table so as to insure effective pressure relation between the pressure rolls and the work throughout its entire width. This is 30 particularly important when working on relatively thin material. The ends of the drum 18 fit snugly against the side walls 12.

One end of the shaft 20 is extended at 90 for 35 connection with a disc sander 92. To the adjacent wall 12 I connect a pair of brackets 94 through the medium of bolts 96. Brackets 94 include curved tracks 97 which slidably receive curved arms 98 connected with a work table 100. Figure 7 illustrates the specific construction of 40 the tracks 97 and their relation with the curved arms 98. In this figure, the curved arm 98 illustrated therein includes a slot 102 extending substantially full length of the arm. A bolt 104 has its head 106 lying between the flanges 108 of the 45 arm, while the bolt extends through the slot 102 and through an opening 110 in the bracket 94. A hand wheel 112 has threaded connection with the bolt 102 for drawing the arm 98 into fixed 50 relation with the bracket 94. Both arms 98 are of identical construction, while one of the arms may be provided with graduations 114 arranged in reading relation with a pointer 116 fixedly connected with the bracket 94 associated therewith. Graduations 114 may be in terms of angles 55 for determining the angular relation between the work table 100 and the work face of the sanding disc 92. Wall 12 is provided with openings 118 for accommodating the arms 98 as the table 100 is being lowered for increasing the angular 60 relation between the table and the sanding disc 92.

In operation, work is pushed through the machine against the rotation of the drum 18. Springs 48 are of sufficient tension to effectively 65 hold the drum in proper pressure relation with the work being finished. In cases where the work is passed through the machine in the wrong direction or the drum 18 is rotated in the wrong direction the work will be pulled underneath the

drum 18. Under such conditions the compression springs 48 will yield to permit the drum 18 to be elevated so as to prevent damage to the machine. Side walls 12 are arranged in right-angular relation to the work table 10. Relatively thin work 5 may be edged by pressing the work against one of the side walls as it is being pushed through the machine.

Shaft 20 is extended beyond one of the walls 12 and carries a grooved wheel 120 for connection with a source of power (not shown).

I claim:

1. An abrading machine comprising a work table, side members, bearing blocks slidably related to the side members, a sanding drum rotatably journaled in the bearing blocks, a screw fixed to each bearing block, sprockets having threaded relation with the screws, an operating chain passing about said sprockets for rotating the screws, to adjust the sanding drum toward and away from the work table, a pair of work pressure rolls, a bell crank support for each end of each of the work pressure rolls pivotally connected with one of said bearing blocks, spring means interconnecting the two bell crank supports at the ends of the work pressure rolls for urging the latter downwardly on the work, and means for limiting the downward pressure movement of the work pressure rolls.

2. An abrading machine comprising a work table, spaced side members, bearing blocks slidably related to the side members, a sanding drum rotatably journaled in the bearing blocks, screw means for adjusting the bearing blocks vertically to shift the sanding drum toward and away from the work table, a pair of work pressure rolls, a pair of bell cranks pivotally connected to each bearing block with each bell crank having a supporting connection with one end of one of the work pressure rolls, spring means connected with the bell cranks for urging the work pressure rolls downwardly on the work, and stop means for limiting the downward movement of the work pressure rolls, said stop means being so arranged with respect to their respective bell cranks as to permit the work pressure rolls to drop to normal positions predetermined distances below the sanding drum, but being so arranged as to hold the work pressure rolls spaced from the work table in elevated positions of the sanding drum.

3. An abrading machine comprising a work table, side members associated with the work table, bearing blocks slidably related to the side members, a sanding drum rotatably journaled in the bearing blocks, screw means operatively connected with the bearing blocks for adjusting the latter relatively to the side members for adjusting the sanding drum toward and away from the work table, a pair of work pressure rolls, and operating connections between the work pressure rolls and said bearing blocks for urging the work pressure rolls into engagement with the work, but operating to limit the downward movement of the work pressure rolls so as to hold the latter spaced from the work table in elevated positions of the sanding drum.

JOHN HOWARD KING.
